(57) **CLAIM**

The ornamental design for an indicator sticker with combined inner and outer portions, as shown and described.

DESCRIPTION

FIG. 1 is a front view of an indicator sticker with combined inner and outer portions showing our new design;

FIG. 2 is a top view of FIG. 1, the bottom view being a mirror image thereof; and,

FIG. 3 is a side view of FIG. 1, the opposite side view being a mirror image thereof.

The dashed broken line portion in the drawings is included to show environment that forms no part of the claimed design. The dot-dash broken line portion in the drawings defines the bounds of the claimed design and forms no part thereof.

1 Claim, 3 Drawing Sheets
